DESIGN FOR A PROJECTOR OR THE LIKE

John T. Armbruster, Niagara Falls, N. Y., assignor to American Optical Company, Southbridge, Mass., a voluntary association of Massachusetts

Application October 18, 1946, Serial No. 134,059

Term of patent 14 years

(Cl. D61—1)

To all whom it may concern:

Be it known that I, John T. Armbruster, a citizen of the United States of America, residing at Niagara Falls, in the county of Niagara and State of New York, have invented a new, original, and ornamental Design for Projector or the Like, of which the following is a specification, reference being made to the accompanying drawings, forming a part thereof.

Fig. 1 is a perspective view of a projector showing my new design;

Fig. 2 is a fragmentary front elevational view of the projector shown in Fig. 1.

The characteristic features of my design are shown in full lines in the drawings.

I claim:

The ornamental design for a projector or the like, substantially as shown and described.

JOHN T. ARMBRUSTER.
